AIR CONDITIONING APPARATUS

Edward R. Wolfert, Springfield, Mass., assignor
to Westinghouse Electric & Manufacturing
Company, East Pittsburgh, Pa., a corporation
of Pennsylvania

Application June 28, 1941, Serial No. 400,162

6 Claims. (Cl. 62—6)

My invention relates to air conditioning apparatus, more particularly to a reversible cycle refrigerating system for either heating or cooling air for comfort, and it has for an object to provide improved apparatus of the character set forth.

A further object is to provide a reversible cycle refrigerating system that may be manufactured at reduced cost.

Another object is to provide a reversible cycle refrigerating system subject to minimum possibility of leakage of refrigerant.

Another object is to provide electrically-energized reversing means so that the cycle of operation may be reversed by merely actuating an electric switch.

In accordance with my invention, I provide a fluid-tight casing enclosing the compressor and the motor which drives the compressor. I dispose the reversing valve, that is, the valve structure which reverses the direction of flow through the condenser and evaporator elements, within the fluid-tight casing, thereby simplifying and reducing the cost of the apparatus, and also minimizing the possibility of refrigerant leakage.

In the preferred embodiment of my invention, I provide a reversible motor for driving the compressor, and I provide means for actuating the reversing valve by and in accordance with the direction of rotation of the motor-compressor unit.

These and other objects are effected by my invention as will be apparent from the following description and claims taken in connection with the accompanying drawing forming a part of this application, in which:

Fig. 1 is a diagrammatic view of a reversible cycle refrigerating system in accordance with my invention;

Fig. 2 is a sectional view of a reversing valve which may be employed; and

Fig. 3 is a wiring diagram of a modified form of control.

Referring to the drawing in detail, I show a reversible cycle refrigerating system including two heat exchangers 10 and 11 which may be of the conventional cross-finned serpentine coil type. Provision is made for conveying air over the coil 10 and delivering the same to the enclosure to be air conditioned. The coil 10 serves as the evaporator during the cooling cycle and as the condenser during the heating cycle. Provision is also made for conveying outside air over the coil 11 and for discharging the same to outdoors or other place exterior of the enclosure.

The coil 11 serves as the condenser during the cooling cycle and as the evaporator during the heating cycle. The runs or tubes of each coil are preferably connected to provide a refrigerant path extending from the top through the successively lower adjacent runs to the bottom of the coil, so that, when the coil is serving as the condenser, the condensed refrigerant flows by gravity to the bottom of the coil.

5 A capillary tube 12, of considerable length and restricted bore, and which is constantly open and provides constant restriction to flow, is connected between the lower ends of the two coils. It serves as the expansion device during both the heating and the cooling cycle.

The refrigerating system further includes a motor-compressor unit 13, which comprises a compressor 14 and a motor 15 directly connected to the compressor for driving the same. The 10 compressor and the motor are enclosed within a hermetically-sealed or fluid-tight casing 16, which contains refrigerant gas at suction pressure. The compressor draws refrigerant gas from the interior of the casing 16, the gas being 15 drawn through the motor for the purpose of cooling the same and then conveyed through a conduit 17 to the compressor. The compressed gas is conveyed from the compressor through a discharge conduit 18 to a reversing valve 19. A 20 reservoir or accumulator 21 is provided in the path of the suction gas to separate out and to retain liquid refrigerant from the suction gas returning from the evaporator. Respecting the 25 arrangement of the accumulator in the system, reference is made to my copending application Serial No. 400,161, filed June 28, 1941, and Serial No. 518,513, filed January 17, 1944. The accumulator 21 is disposed within the casing 16 and its inlet is connected to the reversing valve 19 by a conduit 22. The refrigerant gas is discharged 30 from the top of the accumulator directly into the interior of the casing 16 while the liquid refrigerant is retained therein. The reversing valve 19 is connected to the coils 10 and 11 by means 35 of conduits 23 and 24, respectively.

The reversing valve 19 is adapted to place the compressor suction and discharge in communication with the coils 10 and 11, respectively, or to reverse the connections and place them 40 in communication with the coils 11 and 10, respectively. In accordance with the present invention, the reversing valve is disposed inside the casing 16. While any suitable construction 45 of reversing valve may be used so far as the present invention is concerned, I prefer to use the

one which is shown in Fig. 2 and which will be readily apparent from the drawing. It includes a casing 25 made in three parts and an axially-movable valve member 26 having annular ribs or ridges 27 and 28 which extend into annular recesses 29 and 30 communicating with the conduits 23 and 24, respectively. The discharge conduit 18 communicates with the interior of the casing 25 intermediate the recesses 29 and 30, while the conduit 22 communicates with the right-hand end of the interior of the casing, and also with the left-hand end through passages formed in the valve member 26. When the valve member 26 is moved to the left so that the ribs 27 and 28 seat against the left-hand sides of the recesses 29 and 30, as shown in Fig. 2, the conduit 22 communicates with the conduit 23 and the conduit 18 communicates with the conduit 24. When the valve member 26 is moved to the right to seat the ribs 27 and 28 against the right-hand sides of the recesses, the connections are reversed, the conduit 22 communicating with the conduit 24 and the conduit 18 communicating with the conduit 23. The construction of the reversing valve so far described is in accordance with the above-mentioned invention of John G. Ritter.

In accordance with my invention, I provide common soldered joints for extending the conduits 23 and 24 through the casing 16 and into the casing 25. As shown in Fig. 2, the openings in the casing 16 through which the conduits 23 and 24 extend are of greater diameter than the conduits. The intermediate part of the casing 25 is formed with flanges 31 which encircle the conduits and extend into the spaces between the conduits and the edges of the openings substantially flush with the outer surface of the adjacent portion of the casing 16, which portion is preferably substantially flat. The solder is then applied, as shown in Fig. 2, to contact the conduit, the flange 31 and the casing 16. Accordingly, there is provided by a single soldering operation a seal between the conduit and the casing 25 and a seal between the conduit and the casing 16.

Suitable provision is made for actuating the reversing valve 19. In accordance with a further feature of my invention, it is actuated by and in accordance with the direction of rotation of the shaft 20 of the motor-compressor unit. By using a single phase capacitor motor, the direction of rotation may be readily reversed by connecting the capacitor winding to one side or the other of the electrical supply conductors. This is illustrated in Fig. 1, wherein the double-throw switch 31 is adapted to place the circuit of the capacitor winding, which includes the capacitor 32, to either the line conductor L₁ or L₂. When the capacitor circuit is connected to the conductor L₁, the shaft 20 rotates in clockwise direction as seen in Fig. 1, and when it is connected to the conductor L₂, the shaft rotates in counterclockwise direction. A switch 33 may be provided in the line conductor L₁ to interrupt the supply of current to the motor.

The mechanism for actuating the reversing valve 19 may be of any suitable form. For simplicity of illustration, I show a sleeve 34 which encircles the shaft 20 and which is dragged by the shaft when it is free to rotate. However, it is adapted to slip relative to the shaft when held against rotation. As will be noted from Fig. 1, when the shaft 20 rotates in clockwise direction,

the sleeve 34 moves the movable valve member 26 to the left of the position shown to cause the refrigerating system to operate on the cooling cycle. When the shaft 20 rotates in counterclockwise direction, the sleeve moves the valve member 26 to the right for the heating cycle. A screw 35 is provided to adjust the degree to which the sleeve 34 is clamped on the shaft 20, in order to adjust the degree of drag or slip.

10 The reversible cycle refrigerating system, which is illustrated diagrammatically, may be incorporated in any suitable form of apparatus. It is particularly suited for a self-contained air conditioning unit adapted to be mounted either 15 in the window of a room, or a unit adapted to be placed in a room and connected to the outside with suitable ducts.

Operation

20 Assume that it is desired to cool the enclosure served by the illustrated refrigerating system. The switch 31 is placed in the position illustrated to provide the cooling cycle, and the switch 33 is closed to connect the motor with a source of 25 electric current. The shaft 22 rotates in clockwise direction, moving the valve member 26 to the left to the position illustrated. The system now operates in the usual manner of a refrigerating system. Refrigerant vapor from the interior of the casing 16 is drawn through the motor and the conduit 17 to the compressor where its pressure is increased. The compressed refrigerant is conveyed through the conduit 18, the connecting passage of the reversing valve 19 and 30 the conduit 24 to the outside air coil 11. The condensed refrigerant flows through the capillary tube 12 wherein its pressure is reduced. It then flows through the conditioned air coil 10, wherein it extracts heat from the air which is circulated over the coil 10 and delivered to the enclosure, the refrigerant being vaporized by the extracted heat. The vaporized refrigerant then 35 flows through the conduit 23, the connecting passage of the reversing valve 19, and the conduit 22 and the accumulator 23 to the interior of a casing 16, from which it is recirculated.

To heat the enclosure, the switch 31 is moved to the lower position and the switch 33 is closed. 40 The shaft 20 now operates in counterclockwise direction, dragging the sleeve 34 with it until the valve member 26 is moved to the right. The connections are now reversed so that the compressed gas flows through the conduit 23 to the conditioned air coil 10. As it flows through the coil 10, it gives up its super heat and latent heat to the air circulated over the coil and is thereby 45 condensed. The heated air is delivered to the enclosure to maintain it at a comfortable temperature. The condensed refrigerant flows through the successive tubes to the bottom of the coil 10, from which it enters the capillary tube 12. From 50 the latter it enters the outside air coil 11. As it flows through the latter, it absorbs heat from the outside air flowing over the coil 11 and is thereby 55 vaporized. The vaporized refrigerant discharged from the upper end of the coil 11, flows through the conduit 24, the connecting passage of the reversing valve 19, the conduit 22 and the accumulator 23 to the interior of the casing 16. 60 From the latter it is recirculated through the motor, the conduit 17 and the compressor 14 to the discharge conduit 18.

The operation of the compressor may be controlled thermostatically by a thermostat T. In 65 this case, the switch 33 is replaced by contacts

33a and 33b which are closed when the temperature rises above or drops below a desired temperature range. The switch 31 is replaced by contacts 31a and 31b. The contacts 31a are bridged to provide cooling operation when the temperature rises above the upper limit of the desired temperature zone, and the contacts 31b are bridged to provide heating operation when the temperature drops below the lower limit of the desired temperature zone.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In a reversible cycle refrigerating system for heating or cooling an enclosure, the combination of a compressor, a motor driving the compressor, a fluid-tight casing enclosing the motor and the compressor, first and second heat exchangers, said second heat exchanger being arranged to heat or cool air for the enclosure, means connected between said heat exchangers for reducing the pressure of the refrigerant from condensing pressure to evaporating pressure, reversing valve means disposed within said fluid-tight casing and adapted to selectively connect the suction and the discharge of said compressor to said first and second heat exchanger, respectively, for heating said enclosure or to said second and said first heat exchanger, respectively, for cooling said enclosure, and means operable from the exterior of said casing for controlling said reversing valve means.

2. In a reversible cycle refrigerating system for heating or cooling an enclosure, the combination of a compressor, a motor for driving the compressor, a fluid-tight casing enclosing said compressor and said motor, means for reversing the direction of rotation of said motor, a first and a second heat exchanger, expansion means connected between said heat exchangers, and reversing valve means disposed within said fluid-tight casing and operable upon rotation of said motor in one direction to connect the suction and the discharge of the compressor to said first and said second heat exchanger, respectively, and to said second heat exchanger and said first heat exchanger, respectively, upon rotation in the opposite direction.

3. In a reversible cycle refrigerating system for heating or cooling an enclosure, the combination of a compressor, a motor driving the compressor, a fluid-tight casing enclosing the motor and the compressor, first and second heat exchangers, said second heat exchanger being arranged to heat or cool air for the enclosure, means connected between said heat exchangers for reducing the pressure of the refrigerant from condensing pressure to evaporating pressure, reversing valve means disposed within said fluid-tight casing and adapted to selectively connect the suction and the discharge of said compressor to said first and said second heat exchanger, respectively, for

heating said enclosure or to said second and said first heat exchanger, respectively, for cooling said enclosure, electrically energized means within said fluid-tight casing for actuating said reversing valve means, and means actuated exteriorly of said fluid-tight casing for controlling the energization of said electrically energized means.

4. In a reversible cycle refrigerating system for heating or cooling an enclosure, the combination of a compressor, a motor driving the compressor, a fluid-tight casing enclosing the motor and the compressor, first and second heat exchangers, said second heat exchanger being arranged to 15 heat or cool air for the enclosure, means connected between said heat exchangers for reducing the pressure of the refrigerant from condensing pressure to evaporating pressure, reversing valve means disposed within said fluid-tight casing adjacent the inner side of the wall thereof and adapted to selectively connect the suction and the discharge of said compressor to said first and said second heat exchanger, respectively, for heating said enclosure or to said second and said first heat exchanger, respectively, for cooling said enclosure, conduits connecting said heat exchangers to said reversing valve means, said casing having an opening or openings to provide communication between said conduits and said reversing valve means, and a common soldered joint providing a seal between each conduit and the casing and a seal between the conduit and the reversing valve means.

5. A motor compressor unit for a reversible cycle refrigerating system comprising a compressor, a motor for driving the compressor, a fluid-tight casing enclosing said compressor and said motor, means for reversing the direction of rotation of said motor, and reversing valve means having first and second ports and disposed within said fluid-tight casing, said reversing valve means being operable to connect the suction and discharge of the compressor to said first and said second port, respectively, upon rotation of said motor in one direction, and to said second port and said first port, respectively, upon rotation of said motor in the opposite direction.

6. A motor compressor unit for a reversible cycle refrigerating system comprising a compressor, a motor driving the compressor, a fluid-tight casing enclosing the motor and compressor, reversing valve means having first and second ports and disposed within said fluid-tight casing adjacent the inner side of the wall thereof and adapted to selectively connect the suction and the discharge of said compressor to said first and said second ports, respectively, or to said second and said first port, respectively, conduits connected to said first and second ports of said reversing valve means, said casing having an opening or openings to provide communication between said conduits and said reversing valve means, and a common soldered joint providing a seal between each conduit and the casing and a seal between the conduit and reversing valve means.

EDWARD R. WOLFERT.
